UNITED STATES PATENT OFFICE.

ANDREW M. CLOUGH, OF BATAVIA, NEW YORK, AND JOHN W. CARNOHAN, OF CLEVELAND, OHIO.

WEED PULLER AND BALLAST RENOVATOR.

Application filed June 7, 1923. Serial No. 644,029.

To all whom it may concern:

Be it known that we, ANDREW M. CLOUGH and JOHN W. CARNOHAN, citizens of the United States, residing, respectively, at Batavia, in the county of Genesee and State of New York, and at Cleveland, in the county of Cuyahoga and State of Ohio, have invented certain new and useful Improvements in Weed Pullers and Ballast 10 Renovators, of which the following is a specification.

Our invention relates to mechanism for removing weeds and other wild growth from the space along railroad tracks and for renovating the track ballast. The invention also provides means for cutting sod adjacent the track, and has for its object the provision of an apparatus which may be readily mounted upon a car and drawn over the 20 track without interfering with the passage of trains upon adjacent tracks or deranging any switches or switch-throwing mechanism. The invention has for its object the provision of ground or ballast-engaging devices 25 which may be operated at the sides of a car and easily manipulated to be supported in an inoperative position against the sides of the car above the track or ballast and may be adjusted from time to time as circumstances demand by operators upon the car. The invention also has for its object the provision of simple and easily controlled devices operated by compressed air from the locomotive or the train line whereby 30 manual labor will be minimized, and another object of the invention is to provide means whereby the ballast or ground-engaging elements may be quickly and easily reversed so as to be disposed in proper operative position whether the car is traveling in one or the opposite direction. Incidental objects of the invention will appear in the course of the following description.

In the accompanying drawings, which illustrate one embodiment of our invention,

Figure 1 is a plan view of so much of a railroad car as is necessary to show the mounting of our improved apparatus thereon, the apparatus of our invention being shown in operative position in full lines and dotted lines being employed to show other positions of the ground-engaging elements;

Fig. 2 is a side elevation of the structure shown in Fig. 1;

Fig. 3 is an enlarged transverse section on the line 3—3 of Fig. 1;

Fig. 4 is an enlarged detail section on the line 4—4 of Fig. 3;

Fig. 5 is an enlarged detail section on the line 5—5 of Fig. 2;

Fig. 6 is a perspective view of the slidable crosshead shown in Fig. 5, the parts of the said crosshead being disassembled but approximately in their proper relative positions;

Fig. 7 is an enlarged horizontal section of a four-way valve employed in the apparatus, the plane of the section being indicated by the line 7—7 of Fig. 2;

Fig. 8 is an enlarged detail perspective of 70 means for retaining the ground-engaging elements in an inoperative position;

Fig. 9 is an enlarged vertical section on the line 9—9 of Fig. 3;

Fig. 10 is an enlarged front elevation of 75 one-half of a rake head with the ballast-engaging teeth mounted thereon;

Fig. 11 is a section on the line 11—11 of Fig. 3;

Fig. 12 is a detail elevation of a sod cutter, and

Fig. 13 is a bottom plan view of the sod cutter.

The railroad car, indicated at 1, may be a platform car built especially for carrying our improved weed-pulling and ballast renovating apparatus or it may be an old car modified in such particulars as may be necessary to permit the apparatus to be mounted thereon. The details of the car construction do not form essential features of our invention and the car has, therefore, been illustrated in a more or less conventional manner. In order that the mechanism of our invention may be out of the way when it is not in use, we reduce the width of the car at points between the ends thereof so that recesses 2 are formed in the sides of the car and the ground-engaging elements are supported by devices mounted upon the car at the longitudinal walls of the said recesses, as clearly shown in Fig. 1.

In carrying out our invention, we secure rigidly to the sides of the car uprights 3 which constitute guides for the rake head supports and are provided upon their inner opposed faces with tracks 4 which are preferably constructed of channel metal, as

shown most clearly in Fig. 4, the uprights 3 being preferably angle bars disposed with one web against the edge of the car platform or body and another web projecting laterally therefrom, as also shown clearly in Fig. 4. Fitted slidably between the tracks 4 is a bar 5 which may conveniently be of wood having metal plates 6 secured to its inner and outer faces with their edges projecting beyond the edges of the bar or block 5 so that grooves or ways are produced which fit around the tracks 4 and thereby hold the slide to a rectilinear path between the uprights 3. The uprights may be reinforced by any convenient or preferred means, obliquely disposed braces 7 and gusset plates 8 being illustrated whereby rigid connections between the uprights and the car body are secured. Secured to the inner side of one upright 3 at each side of the car is a locking plate 9 having openings 10 formed therethrough and rigidly secured to and projecting inwardly from the inner side of each slide is a bracket 11 having similar openings 12 therethrough, the openings in the locking plate and in the brackets being adapted to register and receive locking pins or bolts of any convenient type whereby the slide will be positively held at any desired elevation. Each bracket 11 carries a crosshead 13 at its inner end in which is secured the lower end of a piston rod 14 extending from a vertically disposed cylinder 15 and connected with a piston within said cylinder which may be of any convenient form and which, in itself, forms no part of our present invention. Fluid pressure is admitted to the opposite ends of the cylinder 15 so as to shift the piston therein vertically and thereby raise or lower the crosshead through its connection with the piston rod 14. The admission and discharge of the fluid pressure is controlled by means which will be hereinafter more particularly mentioned. To the outer side of each slide we secure a plurality of outwardly projecting brackets upon which a rake head is pivotally supported. These brackets, indicated at 16, may be of any suitable form and are disposed in two series, as will be readily understood upon reference to Fig. 3, the outer ends of all the brackets having vertical openings therethrough to receive pivot pins 17 and 18 respectively. A rake-carrying arm 19, preferably of triangular form, has its inner side provided with eyes 20 engaged around the pivot pin or bolt 17 and supported on said bolt by the adjacent brackets 16, while the outer end of the said arm is provided with an eye 21 receiving a threaded stud 22 at the upper end of the rake head so that the rake head may turn pivotally in the said eye, and a nut 23 is mounted upon the said threaded stud and is turned home

against the upper side of the eye 21 whereby to prevent the rake head dropping from said eye. The rake head is indicated as an entirety by the reference numeral 24 and the threaded stud 22 rises from a triangular coupling plate 25 which is secured rigidly to the body of the rake head at the upper edge thereof. The body of the rake head comprises front and back plates 26 and 27 having spacing bars or blocks 28 disposed between their opposed faces at intervals in the vertical extent of the same and having the coupling plate 25 fitted between their upper edges, as will be readily understood upon reference to Figs. 9 and 10. At the upper and lower edges of the front plate and at the center of the same, we secure angle strips 29 which are provided in their forwardly projecting webs with notches 30 to receive the shanks 31 of teeth 32. The shank-receiving strips are rigidly secured to the rake head by bolts or rivets, as shown at 33, and the shanks 31 are preferably of angular cross section so that they will fit closely within the notches 30 and be thereby prevented from rotating. Clip bolts 34 are fitted around the shanks 31 and through the rake head, as shown clearly in Fig. 11, and nuts 35 are mounted upon the rear ends of these bolts and turned home against the back plate 27 whereby to firmly clamp the teeth to the rake head. The teeth are thus securely clamped to the rake head and each tooth may be adjusted vertically independently of all the other teeth so that, while the teeth may be set to run at any desired depth below the rake head, they may be also set so as to all have their working lower ends disposed in the same horizontal plane, as shown at the left of Fig. 3, or may be disposed in stepped relation, as shown at the right of Fig. 3. The lower ends or points of the teeth are curved so that they project slightly forward and will, therefore, readily pass through the ballast and engage under the roots of any weeds which may be growing along the track and easily remove said growth from the ground. In order that the ballast will not accumulate between the teeth and choke the operation thereof, the alternate teeth are offset rearwardly, as shown at 36, and they are consequently disposed to run in rear of the remaining teeth, as shown clearly in Fig. 2. This arrangement of the teeth does not lessen their weed-pulling efficiency but provides increased clearance between adjacent teeth so that the stones constituting the track ballast will be readily turned aside to permit the passage of the teeth. Secured between the front and back plates 26 and 27, at the ends thereof and projecting beyond said ends, are hinge blocks 37 which are provided at their outer extremities with forks 38, and the forks at the inner end of the rake head

are adapted to engage around the pivot pin or bolt 18 whereby the rake head will be supported by the said pivot and the brackets 16 and may swing pivotally upon the bolt. 5 The forks at the outer end of the rake head are adapted to receive pivotally a pin or bolt 39, and between two of the said forks 38 an eye 40 is engaged around the said pivot, transverse bolts 41 being inserted 10 through the sides of the several forks 38 to retain the respective pivot bolts therein. The eye 40 is part of a coupling which is completed by an arm 42 projecting from the eye and carrying a pivot pin 43 at its rear 15 end. The said pivot pin 43 is engaged in mating eyes on the end of a yoke 44 at the forward end of a strut 45 which strut extends to the side of the car and is provided at its rear end with a yoke 46 similar to the 20 yoke 44 and coupled in like manner to a coupling head 47 which is pivotally mounted in the front end of a slide or crosshead 48. The pivot 43 is disposed at a right angle to the pivot 39 and the pivots connecting the 25 coupling 47 to the yoke 46 and to the slide 48, respectively, are likewise disposed at a right angle to each other so that universal joints are provided at both ends of the strut 45. When the apparatus has reached the 30 limit of travel in one direction or the limit of the scene of operation and it is desired to return to the starting point, the pivot pins or bolts 18 and 39 are withdrawn and the rake heads may then be swung pivotally 35 within the eye 21 so that the teeth 32 will be reversed and their points caused to extend in the opposite direction from that in which they were previously set. The pivot pins are then reengaged in the several 40 brackets and the car may be driven backwardly so that the ballast may be renovated in the opposite direction. If it be desired to return to the starting point without having the teeth in operative position, 45 or when the apparatus is being carried to a point where operations are to begin, the rake heads are adjusted vertically so that the points of the teeth will be above the ballast or the ground level and the rake 50 heads or wings are then swung about the pivots 17 and 18 so that they will lie close to and parallel with the side of the car, as indicated by the dotted lines in the lower portion of Fig. 1. To secure the rake in 55 this position, we provide openings 49 through the rake head in the lower portions thereof and also provide an eye-bolt 50 which is hung upon the side of the car and is adapted to be extended through one of 60 the said openings 49 and be retained therein by a nut 51 turned home on the bolt against the outer side of the rake head, as will be readily understood. The eye-bolt 50 may be mounted upon the side of the car in any 65 preferred or convenient manner, and we

have shown it carried by a short rod or bolt 52 which is fitted in lugs 53 secured rigidly upon and projecting outwardly from the side of the car.

The slide 48 is mounted between and 70 guided by rails 54 secured rigidly in any convenient manner upon the car at each side of the same, and a piston rod 55 has its front end secured to the slide, as shown clearly in Fig. 2, the said piston rod extending from a piston which is disposed within a cylinder 56 securely mounted upon the car at the side of the same, it being understood, of course, that a cylinder 56 with the cooperating piston rod 55 and the rail 54 is provided at each side of the car, as shown in 75 Fig. 1. The slide 48 comprises a body 57 fitting between the upper and lower rails 54 and provided at its inner side with longitudinal flanges 58 adapted to engage the 80 inner sides of the said rails, as shown in Fig. 5, whereby the slide will be prevented from lateral outward movement. Rigidly secured to the outer side of the body is a yoke plate 59 provided on its inner side with 85 a lug 60 adapted to fit within a recess 61 in the outer face of the body 57 so that the accurate assembling of the parts will be facilitated, and this yoke plate is wider than the body 57 so that the inner surface of the 90 yoke plate at the top and bottom thereof will engage against the outer faces of the rails 54, as shown in Fig. 5, whereby the slide will be held to a rectilinear path by the rails. At its rear end, the yoke plate 59 is provided with an outwardly projecting 95 lug 62 in which the front end of the piston rod 55 is secured, and at its front end the yoke plate is provided with the hinge eyes 63 between which the coupling yoke 47 is received and pivotally held by a pin 64. 100 Mounted upon the car between the cylinders 56 is the main supply tank or drum 65, and this supply tank or reservoir is connected by a pipe 66 with the train line, indicated at 67, whereby the supply of compressed air necessary for the operation of the several parts will be maintained from the pump on the locomotive. Preferably, the pipe 66 is disposed at the rear end of the 110 reservoir 65 and it is equipped with a cut-off valve 67 of any desired type. A pipe 68 extends from the front end of the reservoir 65 and branches extend from this pipe to four-way valves whereby the side cylinders 115 56 and the vertical cylinders 15 are supplied and the operation of the pistons in the several cylinders are controlled. The pipe 68 is equipped with a pressure gage 69 so that the attendants may readily know when the supply is becoming exhausted and needs replenishment through the opening of the valve 67. The branch pipes 70 leading from the pipe 68 each communicates with the inlet 120 ports of a pair of four-way valves, indicated 125 130

at 71. By referring to Fig. 1, it will be noted that there are two four-way valves at each side of the car, one of said valves controlling the longitudinal cylinder 56 at the same side of the car and the other of said valves controlling the vertical cylinder 15. The supply pipe 70 leading from the main reservoir communicates directly with the inlet port 72 of the four-way valve and the exhaust port 73 of the valve is disposed diametrically opposite the inlet port. Ports 74 and 75 extend from diametrically opposite points of the valve midway between the ports 72 and 73, as shown clearly in Fig. 7, and these ports 74 and 75 communicate, respectively, with the upper and lower ends of the respective cylinder 15. The body of the valve is provided with passages 76 and 77, and a handle 78 is also provided. When this handle is disposed at an angle of forty-five degrees midway between the exhaust port and the port 74, as indicated by dotted lines in Fig. 7, the ends of the passages 76 and 77 will all be closed by the walls of the valve casing and the valve may be set in this position when the rake is in its lowest position and is working. When the rake is to be supported in a higher position, the valve is set so that the port 75 will be connected with the inlet port 72 and the compressed air will then flow into the lower end of the cylinder 15 and raise the piston therein, the passage 76 establishing communication between the port 74 and the exhaust port 73 at the same time that the ports 72 and 75 are caused to communicate so that the air trapped above the piston may readily escape. To secure the rake in the raised position, the eye-bolt 50 is employed or a holding pin is inserted through the locking plate 9 and the bracket 11 as hereinbefore described. When the rake is in its lowest position, its weight will frequently be sufficient to hold it to its work but it may sometimes happen that the ballast is unusually heavy or the weeds to be uprooted are tough and have attained a thick growth. In such event, the valve may be set to connect the inlet port with the port 74 so that air will be admitted to the upper end of the cylinder 15 and additional pressure thus exerted to hold the rake to its work. The backward thrust upon the rake is, of course, sustained by the strut 45 and the pivots 18 and 39.

The piston in the cylinder 56 is controlled by manipulation of the proper four-way valve in the same manner as that described for controlling the piston in the vertical cylinder 15, but the travel of the piston in the cylinder 56 is, of course, horizontal instead of vertical. If the piston within the cylinder 56 be driven rearwardly, the slide 48 will be drawn rearwardly upon the rails 54 and this movement will be transmitted

through the strut 45 so as to swing the rake head or wing rearwardly about the inner pivots 17 and 18. The rake heads may thus be drawn close to the sides of the car so that they will be inoperative, and, in order to prevent any possible damage by reason of the rake teeth projecting outwardly, the rake head should be reversed before being swung to the side of the car so that the points of the rake teeth will project under the car, as shown by the dotted lines in Fig. 1. It will, of course, be understood that the vertical adjustment or movement of the rake heads permits the operator to elevate them so that they may readily clear switch stands or similar obstructions at the sides of the track without stopping the car or requiring other manipulation of the rakes or of the switches.

As indicated by dotted lines in Fig. 2, a cab 79 will preferably be built upon the car so as to protect the operators from the weather, and within the cab a seat 80 will be provided between each pair of four-way valves so that the operator may assume a comfortable position between the valves and manipulate the same easily and readily as occasion may arise. Two operators will be employed, each operator facing outwardly and controlling the apparatus at his own side of the car. Either rake may be adjusted independently of the other and they may be given vertical movement and a pivotal movement simultaneously or independently. The universal connections at the ends of the struts will permit them to accommodate themselves to the vertical position of the rake heads or wings and at the same time they will very effectually prevent the rakes swinging rearwardly under the strain imposed upon them in uprooting weeds or in renovating the ballast.

When so desired, a ballast guard 81 may be provided to prevent ballast being thrown onto the track rails by the rake. This ballast guard consists of a plate disposed on edge with its lower edge upturned at its front end, as shown at 82, so that it may readily pass over obstructions. This plate is secured at its rear end to a bracket or hanger 83 which is secured at its upper end to a rearwardly projecting lug 84 on an attaching plate 85 which is secured to the back plate 27 of the rake head at the lower corner of the same. The hanger 83 is offset near its upper end, as indicated at 86, so that the ballast guard 81 may clear and project forwardly alongside of the adjacent rake tooth 32.

If grass at the side of the railroad track has grown so rapidly as to form sod choking or overlying the ballast, we may employ the sod cutter shown in Figs. 12 and 13, consisting of a shank 87 similar to the shanks 31 and secured to the rake head in the same

manner. At the end of this shank 87 is a plow or cutter 88 having its front edge beveled or sharpened, as indicated at 89, and tapered forwardly to form a point 90 which will readily penetrate the sod. Secured rigidly to the rear end of the plow or cutter is a deflecting or turning plate 91 which has its rear extremity turned outwardly, as shown at 92, whereby the sod cut by the plow will be turned over and pushed aside beyond the ballast or the track.

Our apparatus is capable of use upon any railroad car and discarded platform cars may be advantageously utilized as mountings for the same. By the use of our apparatus, the ballast of railroad tracks may be very readily and rapidly renovated and weeds or other growths which may spring up in the ballast may be very easily and rapidly removed. When working at the side of the track, the rake teeth will be disposed in stepped relation but when working between two tracks they will preferably be disposed in the same horizontal plane. If circumstances require or suggest, the teeth at one side of the apparatus may be secured in inoperative position and the apparatus set for use at only one side. While the teeth cannot be adjusted vertically in the rake heads instantly, when they have been once set for operation upon a particular stretch of track, no other adjustment of the teeth in the head is needed until the apparatus is to be operated upon a stretch of track having a different depth or in which the ballast has a different conformation.

Having thus described the invention, what is claimed as new is:

1. Apparatus for the purpose set forth comprising a rake, a support for the rake mounted upon the side of a car, the rake being pivotally mounted on said support at a point removed from the side of the car whereby it may be reversed, and means for securing the rake in angular relation to the side of the car while in either position relative to the support.

2. Apparatus for the purpose set forth comprising a rake, a support for the same whereby to mount the rake upon the side of a railroad car, means for bodily adjusting the support vertically upon the side of the car, means for pivotally suspending the rake on the support at a point remote from the side of the car whereby the rake may be reversed, and means for securing the rake in a set position relative to the support and the car.

3. Apparatus for the purpose set forth comprising a support, means for mounting said support on the side of a car for vertical sliding movement, a rake hinged to said support, a swinging arm carried by said

support, and a pivotal connection between said swinging arm and the rake whereby the rake may be reversed or may be swung pivotally upon the support to extend laterally therefrom or lie substantially parallel with the side of the car.

4. Apparatus for the purpose set forth comprising a slide, means for mounting the said slide vertically upon a car, means for shifting said slide vertically, means for locking the slide at any point of vertical adjustment, a rake, means for detachably pivoting either end of the rake to the slide, and means on the slide above the rake for pivotally suspending the rake to permit reversal thereof.

5. In an apparatus for the purpose set forth, the combination with a railroad car, of a rake hinged upon the side of the car and having an opening through its head, and a locking member pivotally suspended upon the side of the car at a point removed from the hinge of the rake and adapted to be inserted through and secured in the said opening in the head of the rake whereby to secure the rake against the side of the car.

6. In an apparatus for the purpose set forth, the combination of a rake head, rake teeth secured to the front side of said head, and a forwardly projecting ballast guard secured to the lower corner of said head and extending past the adjacent teeth.

7. In an apparatus for the purpose set forth, the combination of a rake head, teeth secured to the front side of said head, an attaching plate secured to the rear side of the head at the lower corner thereof, a hanger secured to and depending from said plate, and a ballast guard secured to and projecting forwardly from said hanger past the adjacent teeth.

8. In an apparatus for the purpose set forth, the combination of a slide, means for mounting said slide upon a car for vertical movement, means for maintaining said slide in any position of vertical adjustment, series of brackets secured upon the outer side of said slide, vertically aligned pivots mounted in said brackets, a supporting arm mounted upon the upper pivot, a rake mounted at its inner end upon the lower pivot, said lower pivot being removable from the brackets, a pivot on the upper end of the rake at the center thereof engaged through the outer end of the said supporting arm, and means for engaging the outer end of the rake for maintaining the same in any position of pivotal adjustment.

In testimony whereof we affix our signatures.

ANDREW M. CLOUGH. [L. s.]
JOHN W. CARNOHAN. [L. s.]
